US0D1042477S

(12) **United States Design Patent** (10) Patent No.: **US D1,042,477 S**
(45) Date of Patent: ** Sep. 17, 2024

(54) **DISPLAY SCREEN OR PORTION THEREOF WITH GRAPHICAL USER INTERFACE**

(71) Applicant: **Google LLC**, Mountain View, CA (US)
(72) Inventor: **Hao Zeng**, Seattle, WA (US)
(73) Assignee: **GOOGLE LLC**, Mountain View, CA (US)

(**) Term: **15 Years**

(21) Appl. No.: **29/789,482**

(22) Filed: **Sep. 27, 2021**

(51) **LOC (14) Cl.** 14-04
(52) **U.S. Cl.**

USPC **D14/485**

(57)

CLAIM

The ornamental design for a display screen or portion thereof with graphical user interface, as shown and described.

DESCRIPTION

The sole FIGURE is a front view of a display screen or portion thereof with graphical user interface, showing the claimed design.

The evenly spaced broken lines in the drawings show the electronic device and portions of the display screen or portion thereof with graphical user interface, and form no part of the claimed design.

1 Claim, 1 Drawing Sheet
